DIAL MOUNTING

Eric Beecroft Moss, London, England, assignor to
 S. Smith & Sons (England), Limited, London,
 England, a company of Great Britain

Application January 2, 1945, Serial No. 571,093
 In Great Britain October 12, 1943

3 Claims. (Cl. 58—127)

1

This invention relates to dial mountings for clocks and other instruments. Such dials are usually fixed to their supporting members by means of rivets. It may be desirable for aesthetic reasons that unsightly fixings shall not show, and an object of the present invention is to meet this requirement in a simple manner.

According to this invention, a dial mounting for a clock or other instrument comprises one or more tubular upset portions formed from the material of the dial as by a pressing or punching operation, and a supporting member having one or more holes through which the tubular portion or portions extend and are secured in position by turning over the end or ends. In the case where the supporting member is disposed to the rear of the dial, the upset portions are arranged to extend rearwardly.

A feature of the invention consists in arranging one of the tubular upset portions to perform the dual function of securing the dial to the supporting member and forming the opening through which an indicating member can extend. For example, in the case of a clock, said tubular upset portion is so positioned as to accommodate the arbor carrying the hands.

The supporting member may be resilient in a direction normal to the face of the dial. This arrangement is of advantage in mass production of instruments in which the movement and dial are secured in a definite position within a casing having a cover glass against which a marginal portion of the dial abuts, the resilience of the supporting member enabling different thicknesses of the cover glass to be accommodated without securing the movement in different positions on the casing.

The following is a description of the invention as applied to a 24-hour electric alarm clock, reference being made to the accompanying drawing, in which:

Figure 1 is a front elevation of the dial showing its supporting member in dotted lines,

Figure 2 is a section on the line 2—2 of Figure 1, showing also a part of the clock casing, and

Figure 3 is a fragmentary sectional view taken subsequently on line 3—3 of Figure 2.

As seen from Figure 2, the dial 9 is secured to a supporting member 10 having resilient arms 11, the ends of which arms are attached to the front plate 12 of the movement by being bent at right-angles and their narrowed ends passed through slots 13 and secured in position by bending over or otherwise forming two tapered lugs 55

31 thereon, the shoulders 15 abutting the forward side of the plate 12 adjacent the ends of the slot 13. However, the specific means by which the resilient arms are attached to the front plate 12 in itself forms no part of the present invention. A small inflection 14 is also formed between the arms and the central portion of the supporting member. This central portion of the supporting member has two circular holes formed in it, one in the centre through which the arbor 8 extends, and the other above the centre which forms a window for viewing an indicator disk 16 marked with A. M. and P. M. markings and noon and midnight. The dial 9, which is in the form of a metal plate dished forwardly at 18, carries the usual hour and minute indications 19, and has two holes 20 and 21 corresponding to the two holes in the supporting member and is so formed as to provide rearwardly-extending tubular upset portions 22 which pass through the holes in the supporting member and are swaged outwardly at 23 against the rear face of the supporting member. The dial is thus attached securely to the supporting member without the use of rivets or other unsightly fixing means, and at the same time the edges of the holes are given a smooth radiused appearance. The clock casing 24 is provided with a circular opening in a front wall 25 and a shoulder 26 is formed in this wall around the opening against which the cover glass 30 can be pressed after insertion from the back of the casing. When the glass is in place, the front plate of the movement with the dial held by the resilient supporting member is also inserted from the back so that the periphery of the dished dial engages the glass and so that the front plate of the movement engages another shoulder 27 on the casing to which it is secured by screws 29. The resilience 40 of the arms 11 of the supporting member, especially of the portions outwardly of the bends 14, ensures that the glass is clamped securely in position even if there is a variation in thickness between different glasses.

I claim:

1. A clock dial comprising a metal plate carrying the hour figures and having at least one tubular rearwardly directed upset portion formed integrally therewith, a resilient metal strip having a portion thereon arranged to contact with the metal dial plate and provided with an aperture for accommodating each tubular upset portion, which latter is turned over on the strip, and the other part of which strip is arranged to be spaced away from the metal dial plate and has

its ends bent rearwardly for attachment to a part of the clock.

2. A clock comprising, in combination, a casing having a front opening to accommodate the dial, a dial set in said opening, front stop means limiting the outward displacement of said dial, a resilient strip extending across said opening behind said dial and having a portion lying alongside of and in contact with the rear surface of said dial, said portion having at least one opening therein, at least one tubular upset portion formed integrally with the dial and extending through said opening in the strip, and a turned over end on said upset portion arranged to engage the strip on the opposite side thereof to the dial, a backing element rigid with the casing, and end portions on said resilient strip sprung rearwardly and secured to said backing element, whereby said strip and said dial are urged forwardly toward said front stop means.

3. A clock comprising, in combination, a casing having a front opening therein, a flange around said opening providing a rearwardly facing shoulder, a cover glass extending across said opening and having the margin of its outer face abutting said shoulder, a dial behind said cover glass and having marginal portions pressing forwardly against the rim of said glass, a resilient strip extending across said opening behind said dial

and having a central portion lying alongside of and in contact with the rear central surface of said dial, said portion having at least one opening therein, at least one tubular rearwardly directed upset portion formed integrally with the dial and extending through said opening in the strip, and a turned over end on said upset portion arranged to engage the strip on the opposite side thereof from the dial, radially outer portions of the strip being offset rearwardly from the plane of the dial, a backing element rigid with the casing and the extreme end portions of the resilient strip secured to said backing element, said strip being stressed to urge the dial and the cover glass forwardly against said shoulder.
